UNITED STATES PATENT OFFICE.

MICHAEL E. HEADLAND, OF BUTLER, PENNSYLVANIA.

SANITARY CUSPIDOR.

SPECIFICATION forming part of Letters Patent No. 738,680, dated September 8, 1903.

Application filed March 21, 1903. Serial No. 148,967. (No model.)

To all whom it may concern:

Be it known that I, MICHAEL E. HEADLAND, a citizen of the United States, residing at Butler, in the county of Butler and State of Pennsylvania, have invented new and useful Improvements in Sanitary Cuspidors, of which the following is a specification.

My invention relates to sanitary cuspidors, and has for its object to construct a cuspidor for use in railway-carriages and which will be provided with a false bottom which can be operated to drain the receptacle after using.

The simple and novel construction employed by me in carrying out my invention is fully described and claimed in this specification, and illustrated in the accompanying drawings, forming a part thereof, in which—

Figure 1 is a perspective of my device. Fig. 2 is a vertical longitudinal section thereof. Fig. 3 is a plan view of the same with the cover removed. Fig. 4 is a section on the line 4-4, Fig. 3.

The numeral 1 designates a casing or receptacle which is open at the top and bottom.

25 A shutter 2 is fitted in the receptacle 1 and is pivoted intermediate its ends on a horizontal axle 3, extending transversely the receptacle 1. A pin 4 is seated in the edge of the shutter 2, adjacent to the upper end thereof, and 30 extends through a circular slot 5, traversing one side 6^a of the receptacle 1.

A flaring hopper-shaped top 6 is mounted on the receptacle 1 and is closed by a cover 7, having a conical basin 8 formed therein, which 35 has an aperture 9 in the bottom, which communicates with the receptacle 1. The top 6 projects beyond the slotted side 6^a of the receptacle 1 and has a slot 10 therein, which communicates with a box 11, secured to the 40 side 6^a of the receptacle. The pin 4 extends into the box 11 and is straddled by a fork 12, carried by a slide 13, mounted in a guide-slot 14, formed in the cover 7. Ledges 15 are cut in the sides of the slot 10 to form guides for flanges 16, formed on the fork 12 and held in contact with the ledges 15 by a spring 17. In order to operate the slide 13, an arm 18 is provided, which is serrated to adapt it to be engaged by the toe of a shoe.

45 When in use, my cuspidor is seated in an aperture in the floor of a passenger-coach and the slide 13 set in one of its extreme positions

at one end of the slot 14, with the shutter 2 extending diagonally the receptacle and touching the four sides. After using the cuspidor 55 the arm 18 is engaged with the toe and shifted to its other extreme position, thereby operating the shutter 2 to dump the contents of the receptacle between the tracks.

I do not wish to be limited as to details of construction, as these may be modified in many particulars without departing from the spirit of my invention.

Having described my invention, what I claim as new, and desire to secure by Letters 60 Patent, is—

1. In a cuspidor, the combination of a receptacle open at the bottom but closed at the top by a cover provided with a basin communicating with said receptacle, a plane shutter 70 mounted in said receptacle and centrally pivoted intermediate its ends, said shutter normally extending diagonally said receptacle and being downwardly inclined, and means for operating said shutter to dump the contents of said receptacle, substantially as described. 75

2. In a cuspidor, the combination of a receptacle open at the bottom, a cover for said receptacle provided with a basin communicating with said receptacle, a centrally-pivoted shutter mounted in said receptacle to serve as a false bottom therefor, said shutter extending downwardly and diagonally said receptacle and engaging the opposite walls thereof 85 which serve to limit the movement of said shutter, a slide mounted in a guide-slot in said cover, and means connecting said slide and said shutter to enable them to be operated in unison, substantially as described. 90

3. In a cuspidor, the combination of a receptacle open at the bottom, a cover for said receptacle provided with a basin communicating therewith, a pivoted shutter mounted in said receptacle to serve as a false bottom 95 therefor, a slide mounted in a guide-slot in said cover, a pin carried by said shutter, and a fork carried by said slide and straddling said pin, substantially as described.

4. In a cuspidor, the combination of a receptacle, a shutter pivotally mounted in said receptacle to serve as a false bottom, a pin carried by said shutter and extending through a slot in the side of said receptacle, a cover

for said receptacle provided with a basin communicating with said receptacle, a slide mounted in a guide-slot in said cover, a fork carried by said slide and straddling said pin and an arm carried by said slide and located to be engaged by the toe to operate said shutter, substantially as described.

In testimony whereof I have hereunto set my hand in presence of two subscribing witnesses.

MICHAEL E. HEADLAND.
